UNITED STATES PATENT OFFICE.

FREDERICK M. FISHEL, OF MARION, IOWA.

ENSILAGE-TAMPING APPARATUS.

1,411,428.

Specification of Letters Patent. Patented Apr. 4, 1922.

Application filed April 6, 1921. Serial No. 458,874.

To all whom it may concern:

Be it known that I, FREDERICK M. FISHEL, a citizen of the United States, residing at Marion, in the county of Linn and State of Iowa, have invented certain new and useful Improvements in Ensilage-Tamping Apparatus, of which the following is a specification.

This invention relates to ensilage tamping devices, and more particularly to that type of machine, which may be readily attached and detached from the usual type of silos.

An object of my invention is to provide a suitable ensilage tamping apparatus, which will be efficient in operation and inexpensive to manufacture.

Another object is to provide an apparatus for tamping ensilage which may be so adjusted to readily adapt it for use in connection with any size of silo.

A further object is to provide an ensilage tamping apparatus, which will be provided with a detachable track, which may be readily detached from the silo, in case of an open top silo, or a fixed track in the case the silo was provided with a roof.

Other objects will appear as the description proceeds.

30 In the accompanying drawings which constitute a part of my application.

Figure 1 is a side elevation of my invention, shown partly in section;

35 Figure 2 is a side elevation of a portion of a silo, showing a modified form of track and pulley hangers;

Figure 3 is a side elevation of a silo with my improved tamping mechanism in position thereon;

40 Figure 4 is a plan view of a silo, showing the adjusting means between the track and operating rope or cable, and

Figure 5 is a plan view of a modified form of adjusting hanger between said track and cable.

Like characters of reference are used throughout the several views to designate corresponding parts.

The silo 1 is of the usual construction, 50 and may be provided with or without a roof as desired.

Positioned adjacent the top of the silo 1, and within the same, is a track 2, preferably of T-shape, said track having a plurality of angle members 3, the same being adapted 55 to be attached to the wall of the silo 1,

thereby holding the track in operative position. The angle members may also be hook-shaped as shown at 4, in Figure 2, thereby making it possible to attach to, or detach 60 the track from the silo 1.

The main beam 5 of the derrick is made in sections, and is adjustable in length, by means of the bands 6 which surround both sections of the beam, and a locking bolt 7, 65 which when tightened down, holds the beam at the desired length.

Positioned on the upper end of the beam 5 is a cap member 8, which seats firmly thereon, and formed integrally therewith are 70 a pair of arms or hangers 9, for the reception or positioning of the pulley 10. Adjacent the arms 9, and at either side thereof, are a pair of socket members 11, likewise formed integrally with the arms 9. 75

The bracing beams 12, are of similar construction as the main beam 5, and are provided with the same adjusting and locking means. On the lower ends of the beams 5 and 12 are socket clamps or braces 13, which 80 are provided with downwardly extending flanges 14, for engagement with the sides of the walls of the silo 1.

The main beam 5, also carries at its lower end, the depending arms or brackets 15 for 85 the positioning of the pulley 16. A pulley bracket 17, of U-shape may be employed to carry the rollers 18, for engagement with the inner faces of the T-track, as shown in Figure 1, though I also provide a modified 90 form of square bracket 19, which has one of its sides longer than the other, said sides carrying the pulley rollers 20, which engage on opposite sides of the track, as shown in Figure 2. These brackets 17 or 19 are provided with detachable adjusting means 21, 95 for connecting them with the pulley 22, through which the operating rope or cable 23 extends. A weight 24 is attached to the lower end of the cable 23, and is used for 100 tamping the ensilage in the silo 1.

Figure 5, shows a modified form of adjustable pulley bracket 25, which is provided with the rollers 26, for engagement with the track 2, and the whole being capable of instant removal, or adjustment due to the openings 27 in the bars 28. The pulley 29 which carries the operating rope or cable 23 is mounted on the detachable adjusting device 21, which in turn is connected 110 to the end of the bar 28.

A suitable engine 30 is employed for driv-

ing the operating mechanism 31, which alternatively winds up the cable 23, and then permits it to pull loose, so that the weight 24 may be repeatedly dropped on the ensilage in the silo, thereby tamping the same.

As before mentioned this mechanism may be used in connection with an open top silo, as shown in the drawings, or with a closed top silo, when the two bracing beams will 10 not be used. In this event, the main beam will be laid on top of the roof, and held in position by suitable means (not shown).

Therefore, this mechanism may be permanently positioned in a silo, or detachably secured thereto, in part or the whole.

Many minor changes in detail of construction may be resorted to without departure from the spirit of the invention.

Having thus described my invention what 20 I claim as new and desire to secure by Letters Patent of the United States is:—

1. In an ensilage tamping apparatus, the combination with an adjustable main beam, of a pair of adjustable bracing beams, a 25 track, a pulley engaging the opposite faces of said track, an operating mechanism, a weight, and a cable connecting said weight and operating mechanism.

2. An ensilage tamping apparatus comprising an adjustable main beam, integral 30 sockets carried by said beam, bracing beams engaging said sockets, clamps carried at the

lower ends of said beams, a T-shape track, an operating mechanism, a cable operated by said mechanism, a weight attached to the 35 free end of said cable, and means connecting the track and cable.

3. An ensilage tamping apparatus comprising an adjustable derrick, pulleys carried by said derrick, a track, an operating 40 mechanism, a cable attached at one end to said mechanism, a weight attached at the free end of said cable, a pulley engaging the opposite faces of said track, and adjustable means connecting said pulley and cable. 45

4. In an ensilage tamping apparatus, the combination with a silo, a detachable track in said silo, a detachable derrick positioned above said silo, an operating mechanism, a cable connected to said mechanism, a weight 50 attached to the free end of said cable, and adjustable means connecting said track and cable.

5. In an ensilage tamping apparatus, the combination with a silo, a detachable track 55 in said silo, an adjustable and detachable bracket, pulleys on the ends of said bracket, an operating mechanism, a cable connected to said mechanism, and a weight connected to the free end of said cable, whereby the 60 entire surface of the ensilage may be tamped.

In testimony whereof I affix my signature.
FREDERICK M. FISHEL.
